UNITED STATES PATENT OFFICE.

JOHN W. O'DONNELL, OF SALEM, MASSACHUSETTS, ASSIGNOR, BY MESNE ASSIGNMENTS,
TO THE CARLETON RUHE COMPANY.

LEATHER-WORKING MACHINE.

1,303,840.

Specification of Letters Patent.

Patented May 13, 1919.

Application filed April 5, 1917. Serial No. 160,032.

To all whom it may concern:

Be it known that I, JOHN W. O'DONNELL, a subject of King George V of England, residing at Salem, in the county of Essex and 5 State of Massachusetts, have invented new and useful Improvements in Leather-Working Machines, of which the following is a specification.

This invention relates to improvements in 10 leather working machines and has for its object to provide a machine adapted to so thoroughly perform the process of unhairing hides, skins or the like that the operation known as the fine hairing will be practically eliminated, both operations being accomplished substantially in one and without 15 injury to the hide.

Another object of the invention is to provide a machine which is capable, by very 20 slight adjustment, of accomplishing the fleshing of hides, skins or the like without in the least cutting or damaging the skins.

Still another object of the invention is to provide a machine adapted, in addition to 25 the above, to accomplish the operation known as the putting out of hides or skins, that is to say, stretching or working out the wrinkles or irregularities from the same.

The invention consists in the combination 30 and arrangement of parts set forth in the following specification and particularly pointed out in the claims.

Referring to the drawings:

Figure 1 is a front elevation of a machine 35 embodying my invention, portions of said machine being broken away to save space in the drawings.

Fig. 2 is a right hand side elevation of the same.

Fig. 3 is a vertical section taken on the 40 line 3—3 of Fig. 1. In this figure one of the feed rolls and the bed roll are shown in their forward positions in readiness to receive work.

Fig. 4 is a detail sectional view, illustrating 45 the work members, feed rolls and bed roll of the machine in their operating positions, a piece of work being shown between said rolls.

Fig. 5 is a detail sectional view, similar 50 to Fig. 4, showing a rearrangement of the

working parts of the machine, so as to enable it to perform a fleshing operation on a skin or hide.

Fig. 6 is a front elevation of a portion of 55 one of the work members, showing the difference between the pitch of the helical blades on said member and those of the corresponding work member, shown in Fig. 4.

Fig. 7 is a detail sectional view, similar 60 to Figs. 4 and 5, illustrating the working parts of the machine, adjusted or rearranged to accomplish the putting out of the skins or hides.

Fig. 8 is a detail sectional view taken on 65 the line 8—8 of Fig. 2.

Fig. 9 is a section taken on the line 9—9 of Fig. 3. Fig. 10 is a perspective view of the slicker blade and its supporting member.

Like numerals refer to like parts throughout the several views of the drawings.

In the drawings, 1 represents a base plate of a design suitable to support a pair of side frames 2 and 3, adapted to support the working parts of the machine. When the 75 machine is employed in the unhairing of skins or hides the arrangement of the working parts will be as shown in Figs. 1 to 4 inclusive. In this adaptation two work members 4 and 5 are shown. The work member 80 4 is rotatably mounted upon the side frames 2 and 3 in suitable bearings on said frames and the shaft 6 of said member also constitutes the main driving shaft by which the other working parts are driven.

A driving pulley 7 is attached to the shaft 85 6 and receives its power from any suitable source. The body of the work member 4 is cylindrical and is provided with a plurality of peripheral helical blades 8 which extend 90 from a point, midway of the work member toward the ends in left and right helices in accordance with the construction generally followed in devices of this character. The pitch of each of the helical blades 8—that 95 is, referring to the distance between successive helices measured along a line parallel with the axis of the helix—is preferably 42".

The work member 5 is also cylindrical in 100 construction and provided with a plurality of peripheral helical blades 9 similar to the

blades 8 of the member 4, with the exception that the pitch of the blades 9 is preferably substantially 74''. The work members 4 and 5 are preferably rotated in the same direction, that is, in the direction indicated by the arrows *a* and *b*, the member 5 receiving its power from the member 4 preferably by means of a train of gears, including a gear 10 fast to the shaft 6 which engages a gear 11 attached to one end of an intermediate shaft 12, journaled to rotate in the side frames 2 and 3 at the rear of the work members 4 and 5.

A gear 13 is secured to the opposite end 15 of the intermediate shaft 12 and meshes directly with a gear 14 attached to one end of the shaft of the work member 5. A bed roll 15, provided with a yielding periphery 16 preferably formed of rubber, is arranged 20 to coöperate with the work members 4 and 5, that is to say, the bed roll is mounted upon a rocker frame 17, consisting of two arms 18 and 19 which are pivotally mounted upon a shaft 20 supported by the side frames 2 and 3, above the work members 4 and 5. The arrangement of the bed roll 15 upon the rocker frame 17 is such that when said frame is rocked said roll will be moved into a position between the members 4 and 5 so as to 25 engage said members with equal pressure when moved thereagainst.

The bed roll 15 constitutes a support for the work while being acted upon by the work members 4 and 5, and means are provided 30 to feed the work over said bed roll in opposition to said work members, said feeding means preferably including a pair of feed rolls 21 and 22. The feed roll 21 is journaled to rotate in swivel bearings 15', see 35 Fig. 8, formed in rocker arms 23, mounted adjacent to the inner face of each of the side frames 2 and 3, upon a shaft 24, said shaft being journaled to rock in bearings formed in the side frames 2 and 3. The rocker arms 40 23 are each provided with a lug 25 which normally engages an adjusting screw 26 mounted in each of the side frames 2 and 3. The lug 25 is furthermore yieldingly maintained against the adjusting screw 26 by 45 means preferably including a spring 27, one end of which seats against a collar 28 which abuts against a sleeve 29, said sleeve, in turn, abutting against a stud 30, attached to the rocker arm 23. The opposite end of the 50 spring 27 seats against a collar 31 secured to the end of a rod 32 passing through the center of the spring 27. Said rod also passes through the sleeve 29 and stud 30 toward the front of the machine. The forward end of the 55 rod 32 is screw threaded and engages an adjusting member 33. The adjusting member 33 engages a dog 34 attached to the lower end of an arm 35 depending from the shaft 20.

60 An abutment 36 on the side frame is

adapted to sustain the thrust upon the dog 34, due to the pressure of the spring 27 on the rod 32.

A rotary motion is imparted to the feed roll 21 in the direction of the arrow *c* from 70 the shaft 12 through a train of gears, consisting of a gear 37 fast to the shaft 12 which meshes with a gear 38 rotatably mounted upon the shaft 24.

Secured to the gear 38 is another gear 39 75 which rotates therewith and meshes with a gear 40 attached to the shaft of the feed roll 21. The feed roll 22 is journaled to rotate in bearings 41, 41 carried by the arms 18 and 19 and this roll has motion imparted to it 80 through a pair of gears 42 and 43 secured respectively to the rolls 22 and 21. The teeth of said gears are pointed to permit the same to mesh readily during the movements of the rocker frame 17 toward the feed roll 85 21. The rolls 21 and 22 are each provided with longitudinal corrugations 44 which assist in feeding the work in opposition to the pressure applied thereto by the work members 4 and 5 which are rotated in an 90 opposite direction to said feed rolls.

In addition to the longitudinal corrugations 44 the feed roll 22 is also provided with a series of circumferential corrugations 45 95 which assist in preventing a movement of the work longitudinally of the feed roll. The bed roll 15 is preferably adjustably and yieldingly mounted upon the rocker frame 17 so as to permit the same to be adjusted to contact with equal pressure against the members 4 and 5 and to slightly yield to accommodate any variation in thickness of hides or skins that are to be treated by the machine.

For this purpose the bed roll 15 is journaled to rotate in swivel bearings 15' similar 100 to those illustrated in Fig. 8. The bearings 15' are mounted in bearing members 46, 46 pivotally attached at 47 to pivotal members 48 pivoted at 49 to the lower ends of the arms 18 and 19. Upon opposite sides of the 105 pivot 47 of each of the members 46 are adjusting screws 50, 50 which engage the bearing members 46 and by suitable manipulation are adapted to rock the bearing members 46 about the axes of their pivots 47. The 110 pivotal members 48 are provided with lugs 51 bearing adjusting screws 52 adapted to engage portions of the arms 18 and 19 and thereby prevent the movement of the roll 15 115 relatively to the arms 18 and 19 in the direction of the members 4 and 5 when the rocker frame 17 is stationary.

Each of the pivotal members 48 has an arm 53 which has attached thereto a rod 54. Encircling the rod 54 is a spring 55 which 120 abuts at one end against a collar 56 which, in turn, engages arms 57 projecting forwardly from the arms 18 and 19. The opposite end of the spring 55 abuts against an adjusting member 58 which has screw 125

threaded engagement with the end of the rod 54, whereby the tension of the spring 55 may be adjusted. By means of the spring 55 and its coöperating parts a yielding pressure will be applied to maintain the adjusting screw 52 against the coöperating portion of the arm of the rocker frame adjacent thereto and incidentally permit the bed roll 15 to yield slightly, as hereinbefore described.

The rocker frame 17 is adapted to be oscillated after the work has been placed over the bed roll 15 and the feed roll 22, preferably by means of cranks 59 attached to opposite ends of a shaft 60 journaled to rotate in the side frames 2 and 3. The cranks 59 are connected to the arms 18 and 19 by connecting rods 61. Motion is imparted to the shaft 60 preferably from the driving shaft 6. This motion is slow and adapted to be controlled by the operator.

The preferred method of operating said shaft consists of a worm gear 62 fast to the shaft 60 and engaging a worm 63 secured to a shaft 64 journaled to rotate in bearings 65. The shaft 64 is operated through miter gears 66 and 67 from a shaft 68 which, in turn, receives its motion through a train of gears, including a spur gear 69 rotatably mounted upon the shaft 68 and adapted to be connected therewith by means of a clutch of any of the well known types, one form of which is shown at 70. The gear 69 meshes with an intermediate gear 69' and a gear 71, rotatable with the gear 69', in turn engages a gear 72 fast to the driving shaft 6.

The operation of the machine hereinbefore specifically described is as follows:

40 A hide or skin is laid over the feed roll 22 preferably with one-half or a little more than one-half of said hide projecting downwardly from the side of said roll toward the feed roll 21, the flesh side of said hide being 45 against the feed roll 22. The work members 4 and 5 and the feed roll 21 are at this time being rotated from the shaft 6. The operator next operates the clutch 70 to connect the shaft 68 with the gear 69, thereby 50 imparting a rotary movement to the worm gear 62 to advance the feed roll 22 to the feed roll 21, while the bed roll 15 moves with the hide to press said hide against the work members 4 and 5.

55 Immediately upon the engagement of the teeth of the gear 42 with those of the gear 43 the work, which previously simply laid over the roll 22, will be moved in the direction of the arrow *c* by the feed rolls in opposition to the action of the work members 4 and 5. The pressure of the bed roll 15 against the blades of the members 4 and 5 causes said blades to scrape the hair from the side of the hide. This operation is 60 greatly facilitated by the lower work mem-

ber 4 rotating in the same direction as the work member 5 but at a greater rate of speed, thus drawing the hide tightly over the bed roll 15 and maintaining said hide taut while the slower moving member 5 continues to remove the hair.

The arrangement of the helical blades upon the members also tends to stretch the hide longitudinally of the rolls as well as in the other direction. After the portion of the 75 hide, which was below the feed roll 22 when the operation started, has been treated by the work members, the rocker frame 17 is returned to its former position by again throwing in the clutch which was thrown 80 out when said frame arrived at its innermost position. This moves the rolls 22 and 15 back to their former positions and the hide or work thereon is turned end for end so as to leave the untreated portion thereof 85 suspended from the roll 22 and directed toward the work members. The operation is then repeated.

The bed roll 15 is not disposed directly beneath the feed roll 22 when the rocker frame is forward, as shown in Fig. 3, but is farther toward than said roll 22 in order to permit the skin, which has been placed upon said feed roll 22 in readiness to be advanced to the work members, to hang freely 90 from said feed roll without touching the bed roll. Should said skin be permitted to touch said bed roll when being laid over the feed roll prior to its being fed to the work members a wrinkle or slackness is likely to 95 be formed and if this is not removed before the work members contact therewith the skin will be cut or torn by the sudden tightening thereof. This arrangement is made possible by mounting the bed roll and feed 100 roll 22 upon the rocker frame which is pivoted to rock about an axis disposed above the work members, thus causing the bed roll to move through a longer path than that traversed by the feed roll 22.

110 Another advantage resulting from this arrangement is that less power will be required to move the feed rolls into operative relation with their coöperating members, the weight of said frame and roll mounted 115 thereon being nearly sufficient to produce all of the pressure required.

In Fig. 5 is shown in detail the arrangement of the working parts as used in the fleshing operation. During this operation 120 the face of the hide, rather than the back or flesh side, is arranged in contact with the bed roll 15 and in view of this fact the rolls 21 and 22 have been transposed, that is to say, the roll 22, in the form shown in 125 Fig. 3, which includes both the longitudinal and circumferential corrugations, is put in place of the roll 21 which is transferred to the position previously occupied by the roll 22; thus the roll with the longitudinal cor- 130

rugations will engage the face of the work and not mark or mar the face, as would be the case were the roll 22 permitted to operate thereagainst.

5 Furthermore, instead of the work member 5 being used in this form a work member 73 is provided which differs from the work member 5 only in the pitch of the blades 74 thereof, which are preferably of substantially 10" pitch, whereas those of the member 5 were of 74" pitch. The lower work member 75 of this form is identical with that illustrated in Fig. 3 and operates at a suitable speed, whereas the member 73 is 15 arranged to operate much faster than the member 75.

The blades 74 of the member 73, rotating in the direction of the arrow shown in said figure, remove all of the flesh from the 20 hides, this being assisted by the member 75 which rotates in the same direction and helps to maintain the hide taut during the feeding thereof and during the removing of the flesh by said member 73.

25 In Fig. 7 I have shown another arrangement of the working parts of the machine, especially adapted to the putting out of skins and hides, that is to say, to the spreading and stretching of the hides in both directions in order to remove wrinkles, natural grain and water from the hide. In carrying out this feature of the invention, instead of using the corrugated feed rolls shown in the figures previously described, 30 felt rolls 76 and 77 are inserted instead of the rolls 21 and 22.

The work members 78 and 79 are the same as the work members of the unhairing machine, that is, the member 78 has helical 40 blades 80 of substantially 74" pitch and the member 79 has helical blades 81 of substantially 42" pitch. The members 78 and 79 are rotated in the direction of the arrows *e* and *f* in opposition to the feeding movement of the skin by the rolls 76 and 77, which movement is in the direction of the arrow *g*.

In place of the bed roll 15 which has a rubber surface a member 82 is employed, 50 said member being mounted in place of the member 15 and preferably consisting of a bed 83 of substantially two-thirds of a circle directed toward the members 78 and 79. On this bed is placed a strip of resilient material, preferably felt 84, and over this is laid a strip of leather 85, said felt and leather constituting a bolster which is adapted to support the hide shown at 86 in a position to be operated on by the members 78 and 79.

Attached to the bed 83 is a slicker blade 87 provided with a slightly rounded nose 88 which is directed between the members 78 and 79 and works upon one side of the 65 skin or hide while the work members 78 and

79 are working upon the other face thereof. The work member 79, rotating faster than the work member 78 and in the direction of the arrow *f*, causes the work to be drawn taut over the slicker blade 87 while the pull 70 of the feed rolls 76 and 77 feeds the work between the work members and slicker blade.

With this arrangement, the skin or hide, after being treated on one side by the work member 79, is then worked upon its opposite 75 side by the slicker blade 87, and this work is intensified because of the position of the slicker blade 87 being not only between the work members 78 and 79 but because of the fact that it is placed far enough between 80 said work members 78 and 79, bringing the working point of said slicker blade considerably beyond a plane tangent to the working surfaces of said work members.

This results in breaking the hide over the 85 point of the slicker blade at an acute angle, thereby greatly increasing the strain and stretch upon the hide and resulting in the drawing out of wrinkles and the working of fibers in a superior manner. The hide, 90 after passing from the slicker blade 87, is then subjected to the action of the work member 78 which engages the opposite side of the work from that engaged by said slicker blade. 95

By combining the slicker blade with the two work members, the operation, commonly known as staking, which is the softening and stretching of tanned leather and which is now accomplished on machines constructed solely for that purpose, may be accomplished simultaneously with the regular functions of this machine, thereby resulting in a great saving of time and of labor. 100

In performing the respective operations of unhairing, fleshing and setting out of hides and skins the two work members are preferably adjusted so that the lower work member will revolve at suitable rates of speed in each of the several operations and 110 the upper work member will also revolve at suitable ratios of speed to the lower work member in each of the several operations.

Having thus specifically described my invention what I claim and desire by Letters 115 Patent to secure is:

1. A machine of the character described having, in combination, a work member, a work supporting member, a pair of work feeding rolls acting independently of said work supporting member, a pivoted frame adapted to support said work supporting member and one of said feed rolls, the axis of said frame being disposed above said work member, said work supporting member being adapted by reason of the position of said axis above said work supporting member to move downwardly toward said work member whereby the weight of said frame and said work member will assist the 120

125 130

movement of said work supporting member into engagement with said work member and means for operating said pivotal frame to move the member carried thereby toward 5 and from said work member.

2. A machine of the character described having, in combination, a stationary frame, a pair of work members rotatably mounted in said frame, each of said work members 10 having peripheral helical blades, a feed roll yieldingly mounted upon said frame, means for rotating said feed roll, a rocker frame pivotally mounted upon said frame to rock about an axis disposed above said work 15 members, a second feed roll upon said rocker frame in coöperating relation with the feed roll of said frame, a work supporting member also mounted upon said rocker frame in coöperating relation with said pair 20 of work members, and means adapted to operate said rocker frame to move the member thereon toward or away from the rolls in said frame.

3. A machine of the character described 25 having, in combination, a stationary frame, a feed roll rotatably mounted on said frame, a pair of work members rotatably mounted on said frame, means for rotating said members, a rocker frame arranged to rock about 30 an axis disposed above said feed roll, a second feed roll rotatably mounted on said rocker frame, a work supporting member rotatably mounted on said rocker frame, and means for rocking said frame about its 35 axis to respectively move the feed roll thereon into coöperating relation with the feed roll on said frame and said work supporting member into coöperating relation to said working members.

4. A machine of the character described 40 having, in combination, a pair of coöperating feed rolls, a work supporting member, a work member constructed and arranged to engage the work upon the opposite side thereof from said work supporting member, means for operating said work member in opposition to said feed rolls, and means for engaging the work behind, adjacent to and upon the same side thereof with said work 45 member, adapted to maintain the work under tension while passing between said work member and said work supporting member.

5. A machine of the character described 55 having, in combination, a work supporting member, means for feeding the work over said work supporting member, a work member provided with peripheral helical blades adapted to engage the work upon the opposite face thereof from said work supporting 60 member, said blades being of substantially 74" pitch, a second work member also provided with peripheral helical blades adapted to engage the work upon the opposite face thereof from said work supporting member, 65 the helices of said second work member be-

ing of substantially 42" pitch, and means for rotating said work members in opposition to said feeding means.

6. A machine of the character described having, in combination, a work supporting 70 member provided with a yielding periphery, means for feeding the work over said work supporting member, a work member provided with peripheral helical blades adapted to engage the work upon the opposite face 75 thereof from said work supporting member, said blades being of substantially 74" pitch, a second work member also provided with peripheral helical blades adapted to engage the work upon the opposite face thereof 80 from said work supporting member, the helices of said second work member being of substantially 42" pitch, and means for rotating said work members at different speeds and in opposition to said feeding 85 means.

7. A machine of the character described having, in combination, a pair of work members, each provided with peripheral helical 90 blades, the blades of one of said members being of substantially steeper pitch than the other, a work supporting member having a resilient periphery adapted to support the work between and against the blades of 95 both of said work members, means for rotating both of said work members, the surface speed of the member of steeper pitch being less than that of the other, and means independent of said work supporting member for feeding the work between said work 100 members and said work supporting member in opposition to the movements of said work members.

8. A machine of the character described having, in combination, a stationary frame, 105 rotatable work members mounted upon said stationary frame, said work members having peripheral helical blades, means for rotating said work members, a feed roll mounted to rotate on said frame, means for 110 rotating said feed roll, a rocker frame pivoted to rock about an axis disposed above said feed roll, a second feed roll rotatably mounted upon said rocker frame adapted to coöperate with and be rotated from said 115 first named feed roll, one of said feed rolls being yieldably disposed relatively to the other, a work supporting member yieldingly mounted upon said rocker frame adapted to be moved into operating relation with said 120 work members, and means for operating said rocker frame to move said second named feed roll and said work supporting member respectively toward and away from said first mentioned feed roll and said work 125 members.

9. A machine of the character described having, in combination, a pair of work members, a rocker frame mounted to rock about an axis disposed above said work 130

- members, a pair of bearing members pivotally mounted at opposite sides of said rocker frame, a work supporting member mounted on said bearing members, means for exerting a yielding pressure upon said work supporting member, means for rocking said rocker frame to move said work supporting member between said work members, whereby the work will be pressed thereby against
- 5 10 both of said work members, means for feeding the work between said work supporting member and said work members, and means for operating said work members in a direction opposite to that of said work.
- 15 20 25 30 35 40 45 50 55 60 65 70 75 80 85 90 95 100 105 110 115 120 125 130 135
10. A machine of the character described having, in combination, a pair of work members, each provided with a plurality of peripheral helical blades, the blades of one of said work members being of substantially 42" pitch and the blades of the other of said members being of substantially 74" pitch, means for rotating said work members in the same direction, means for supporting and forcing the work between and against the helices of said work members, and means for feeding the work in a direction opposite to the movements of said work members.
11. A machine of the character described having, in combination, a pair of work members, a feed roll arranged above said work members, a second feed roll constructed and arranged to coöperate with the first named feed roll to feed the work, a work supporting member constructed and arranged to co-operate with said work members to operate upon the work, and means for moving said second feed roll and said work supporting member toward and from the first named feed roll and said work members, said movable feed roll being arranged to the rear of said work supporting member when in its forward position, whereby the work supported by said feed roll may be freely suspended therefrom.
12. A machine of the character described having, in combination, working cylinders, a supporting member consisting of one or more faces adapted to hold the work in contact with said working cylinders, a slicker blade projecting from the face of said supporting member, adapted to support the work in contact with said working cylinders, means for moving said supporting member toward and from said working cylinders, and a pair of coöoperating feed rolls working independently of said working cylinder for drawing the work between said supporting member and said working cylinders.
13. A machine of the character described having in combination, a work-supporting member, means for feeding the work over said work-supporting member, a work-member provided with peripheral helical blades adapted to engage the work upon the opposite face thereof from said work supporting
- member, a second work member also provided with peripheral helical blades adapted to engage the work upon the opposite face thereof from said work-supporting member, the helices of said second work member being of a different pitch, from the helices of the first work member, and means for rotating said work members in opposition to said feeding means.
14. A machine of the character described having, in combination, a work-supporting member, provided with a yielding periphery, means for feeding the work over said work-supporting member, a work member provided with peripheral helical blades adapted to engage the work upon the opposite face thereof from said work-supporting member, said blades being of a certain pitch, a second work member also provided with peripheral helical blades adapted to engage the work upon the opposite face thereof from said work-supporting member, the helices of said second work member being of a certain different pitch, and means for rotating said work members at different speeds and in opposition to said feeding means.
15. In a machine of the character described and in combination, a work-supporting member, means for feeding the work over said work-supporting member, a pair of simultaneously coöoperating work members, each adapted to engage the work upon the opposite face from the work-supporting member, each of said work members being provided with a plurality of peripheral helical blades, the pitch of said helical blades being different in each work member, and means for operating said work members in opposition to said means for feeding the work and at different rates of speed for each work member.
16. In a machine of the character described and in combination a work-supporting member of yielding periphery, means for feeding the work over said work-supporting member, a work member provided with a plurality of peripheral helical blades of certain pitch adapted to engage the work upon the opposite face from said work-supporting member, coöoperating simultaneously with a second work member provided with a plurality of peripheral helical blades of different pitch adapted to engage the work upon the opposite face from the work-supporting member and means for operating said work members in opposition to said means for feeding the work and at different rates of speed for each work member.
17. In a machine of the character described, the combination with a work-supporting member of means for feeding the work over the same, and two knife cylinders rotating at different speeds and coöoperating simultaneously with said work-supporting member, said knife cylinders being provided

with spiral blades of different pitch, said knife cylinders rotating in the same direction and in opposition to said feeding means.

18. In a machine of the character described, the combination with a work-supporting member of means for feeding the work over the same, and two knife cylinders rotating at different speeds and coöperating simultaneously with said work-supporting member, said knife cylinders being provided with spiral blades of different pitch, the surface speed of the cylinder of steeper pitch being less than that of the other.

19. In a machine of the character described, the combination with a work-supporting member having a yielding periphery

of means for feeding the work over the same, and two knife cylinders rotating at different speeds and coöperating simultaneously with said work-supporting member, said knife cylinders being provided with spiral blades of different pitch, the surface speed of one of the knife cylinders being less than that of the other so as to allow for the variation in the pitch of the blades of the two cylinders. 20 25

In testimony whereof I have hereunto set my hand in presence of two subscribing witnesses.

JOHN W. O'DONNELL.
